UNITED STATES PATENT OFFICE.

JOHN C. WILSON, OF BOSTON, AND MILTON G. DAVIS, OF WEST SOMERVILLE,
MASSACHUSETTS; SAID DAVIS ASSIGNOR TO SAID WILSON.

ELECTRIC-SIGNAL BOX.

SPECIFICATION forming part of Letters Patent No. 288,526, dated November 13, 1883.

Application filed July 13, 1883. (No model.)

To all whom it may concern:

Be it known that we, JOHN C. WILSON, of Boston, county of Suffolk, State of Massachusetts, and MILTON G. DAVIS, of West Somerville, county of Middlesex, State of Massachusetts, have invented an Improvement in Electric-Signal Boxes, of which the following description, in connection with the accompanying drawings, is a specification, like letters 10 on the drawings representing like parts.

Our invention, relating to a district or police system signal-box, is intended as an improvement on the signal-box previously invented by J. C. Wilson, for which applications 15 Nos. 92,633 and 92,681 were filed April 23, 1883. In the present invention the multiple-signaling mechanism, substantially the same as described in the said application No. 92,681, is contained in a strong inclosing-case having 20 a movable door or cover controlled by a lock, and also having an opening or key-hole independent of the door-lock, through which a key may be inserted and operated to start the box, the said key being called the "starting-key" 25 or "citizen's key" to distinguish it from the door-key by which the door is unlocked. The said starting-key is engaged immediately after it is operated to start the box, and cannot be thereafter removed until the door of the box 30 is opened by an authorized person having a key to the door-lock, the said door controlling the holding or locking device for the starting-key. In using the box as a part of a police system the starting-keys are distributed among 35 responsible citizens, they being properly numbered for identification, and the policemen have door-keys for the boxes, they alone having access to the interior of the boxes and multiple-signal mechanism therein. The pointer 40 for operating the multiple-signaling device is controlled by the door of the box, it being automatically restored to its normal position when the door of the box is closed, so that the signal transmitted from the exterior of the 45 box by the citizen is always the same. The box has an additional pull or starting device, accessible at its interior when the door is open, to send the desired one of the multiple signals.

Figure 1 is a front elevation of a signal-box 50 embodying this invention, the door being open or removed, affording access to the multiple-signal pointer and inside pull or starting device; Fig. 2, a horizontal section thereof, looking upward or in the direction of the arrow 55 20, Fig. 1; Fig. 3, a detail showing the key locking and releasing device; Fig. 4, a detail showing a portion of the internal mechanism of the box; Fig. 5, a side view of the internal starting device shown in Fig. 4; Fig. 6, a 60 side elevation of the pointer for operating the multiple-signaling device; and Fig. 7 an elevation of the interior mechanism of the signal-box on a larger scale, one of the frame- 65 plates being removed.

The internal signal-producing mechanism, A, inclosed in a strong case or box, B, consists, essentially, of a train of wheel-work, a 70 a', terminating in an escapement, b b'. The shaft c of the wheel a', carrying the break-wheel c', co-operates with the spring d to send a signal for the number of the box or station. The said shaft c also carries a revolving pin or contact-spring, e, co-operating with the 75 different surfaces of the multiple-signal device or drum e', which is concave, as shown, so as to be touched by the spring e in its revolution. The surface of the said drum is cut away or recessed, as shown, so that when turned on its shaft e', to present different sides 80 to the spring e, the latter will make and break electrical connection with the said drum to produce different signals. The break-wheel 85 c' has a long notch, so that in its revolution with the spring e it will remain wholly disconnected from the spring d while the spring e is sweeping over the surface of the drum e'. The spring e is insulated from the shaft c, but connected with a metallic disk, f, on the said shaft, in contact with a stationary spring, f', 90 which, with the spring d, is connected with one end of the main circuit entering the box, while the metal frame-work, including the break-wheel c' and multiple-signal drum f, are connected with the other end of the main circuit, which is completed from the said springs d and e to the said wheel or drum, and is broken as the the said wheel and spring e are 95

revolved by the motor, the breaks taking place in accordance with the shape or notching of the said wheel and that one of the surfaces of the drum e' that happens to be placed in the 5 path of the spring e . The especial signal produced by the spring e and drum e' is preferably sent in advance of the number-signal produced by the spring d and wheel c .

The wheel a of the train of wheel-work or 10 motor by which the signals are produced is loose on the main or winding shaft i , and is provided with a pawl, h , which is engaged by a ratchet, i' , fixed on the said shaft i , and which is acted upon by a spring, i^2 , tending 15 to turn it in the direction to actuate the said train. The winding-shaft i is extended to the side of the outer case, B , where its end is provided with a spindle, i^3 , to receive a citizen's or starting key inserted through a suitable key- 20 hole, k , in the side of the said case. The said shaft is also provided with a projection, i^4 , to be engaged by the key-bit, so as to enable the shaft to be turned by the key to wind up the spring i^2 and present a new tooth of the ratchet 25 i' to the pawl h , carrying the train, to turn under the stress of the spring i^2 as soon as the operator lets go of the key. When the citizen's key is thus inserted and turned it is engaged by a key holding or locking device, m , 30 (shown in this instance as a gravitating pawl pivoted at m' , see Fig. 3,) which drops behind the bit of the key, preventing it from turning backward far enough to be withdrawn from the key-hole. A stop, m^2 , prevents the forward rotation of the key after it has turned the 35 shaft i a sufficient amount, so that it is securely locked in the key-hole, although it can be turned sufficiently to send in the alarm any desired number of times. The citizen's key is released when the proper officer arrives and 40 opens the door of the box by the key-releasing device n , shown as a sliding frame provided with a pin, n' , and acted upon by a spring, n^2 , tending to move it in the direction 45 to cause the said pin to act upon an inclined surface, m^3 , of the locking device m , so as to turn the latter on its pivot and remove it from the path of the bit of the citizen's key. The releasing device is restrained from being moved 50 by the spring n^2 by a projection, n^3 , on the door C of the case B when closed, as shown in Fig. 2, the said door being controlled by a lock, L , of any suitable construction, itself operated by a door-key, with which the policeman or other 55 authorized officer is provided.

When the door of the box is opened, the multiple-signal drum e' may be turned to any desired position by a pointer, P , fixed upon the shaft e^2 of the said drum, the said pointer 60 operating with the dial D , filling substantially the whole opening of the box B , and having marked upon it the different signals that might be sent, as shown in Fig. 1, the drum e' and dial being capable of accommodating a very 65 large number of signals, of which only a comparatively small number are shown in Fig. 1.

When the pointer has been turned to the desired signal, the shaft i may be turned to wind the spring i^2 , to cause the motor to transmit the signal by the internal pull or starting device, o , having a sliding movement in a guide, o' , and being provided with a stud or projection, o^2 , that engages an arm, o^3 , on the shaft i , rotating the said shaft as the pull or handle o is drawn outward, and thus having the same 75 effect as the citizen's key upon the said shaft. The said pull is provided with a retracting-spring, o^4 , which draws it back independently of the action of the spring i^2 on the shaft i . The shaft i is provided with a stop-arm, i^5 , 80 which, by its engagement with the stop-projection p , limits the movement of the shaft i and train of wheel-work, when actuated by the spring i^2 , and in order to arrest the arbor c , with the break-wheel c' thereon, in exactly the 85 proper position with relation to the spring d , the said arbor is provided with a secondary stop-arm, r , which is engaged and arrested by a movable stop, r' , pivoted upon the frame-plate of the wheel-work, and provided with a 90 releasing-arm, r^2 , upon the other side of the said frame-plate, adapted to be engaged by the main stop-arm i^5 , to thus release the secondary stop-arm r when the spring i^2 is wound to actuate the train, the arm r moving beyond its 95 stop r' before the releasing-arm r^2 thereof is disengaged by the main stop-arm i^5 in its return movement.

It is essential that when the box is closed and the signal operated by the citizen's key 100 from the outside the same signal should always be given; or, in other words, that the multiple-signal drum e' should always be in the same position, which is accomplished by providing the pointer P with a cam, t , (shown 105 as spiral in shape,) it co-operating with a projection or friction-roller, u , upon the interior of the door C . In closing the door the said roller engages the cam, and causes it and the connected pointer and drum e' to rotate until 110 the lowest point of the said cam is under the said roller, when, as shown in Fig. 1, the pointer is vertical. Thus when the door is closed the pointer and drum e' are always in the same position, and the same one of the surfaces of the said drum co-operates with the spring e . The surface of the drum that thus 115 co-operates with the spring e when the door of the box is closed is preferably blank, so that the citizen's signal is merely the number of the box, or that produced by the break-wheel c' , which signal will be understood as a call for police. The door C has a central recess, R , for the cam of the pointer P , and an annular recess, R' , for the knob or handle P' of the 120 said pointer, so that the latter can revolve freely under the influence of the cam t and roller u while the door is being closed.

It is intended that the police or watchmen 125 on going their rounds shall open the box and send a signal—for instance, "patrol," which 130 will be understood as signifying that all is

right, and if this signal is not received at the proper time an officer will be sent to find out the cause, as the failure to receive the signal will indicate that the watchman is either negligent or in trouble.

5 It is not new to release a spring-actuated signaling-motor by a key-insertion from the outside of the box, nor to lock or retain such a key to indicate the person that thus operated the box; but by having the actuating-spring of the motor wound by key thus inserted it is possible to repeat the signal as often as desired—a result that has not been previously attained, so far as we are aware.

10 15 We claim—

1. In a signal-box, a motor for actuating a circuit-breaker, and an inclosing-case therefor, the said motor comprising a winding-shaft adapted to be turned by a winding-key inserted from the outside of the said case to wind the actuating-spring of the motor, and thereby cause the said motor to operate, as described, combined with a locking or retaining device for the said winding-key, whereby it is 20 25 retained in the case, but permitted to turn freely when inserted therein for the purpose of giving a signal, substantially as described.

2. The motor for transmitting a signal, and inclosing-case therefor, having a movable door or cover, the said motor being adapted to be actuated by a key inserted from the outside of the case, combined with a locking or retaining device for the said key, and a releasing device therefor controlled by said door, substantially as described.

3. The motor for transmitting a signal, and an inclosing-case therefor, the main or actuating shaft of the said motor being adapted to be engaged by a key inserted from the outside 30 35 of the case, and provided with an arm, combined with an independent starting device accessible only at the interior of the case, co-operating with the said arm, substantially as described.

4. A signal-box containing a multiple-sig-

naling device and a pointer or handle to set it to transmit any desired one of the signals, combined with an inclosing-case having a movable door co-operating with the said pointer, whereby the multiple-signal device is always set to 50 a single definite position when the door is closed, substantially as described.

5. In a signal-box, the motor and its inclosing-case, having a movable door, the actuating or winding shaft of the said motor being 55 adapted to be engaged and operated by a key from the outside of the case, combined with the pivoted key-retaining device and its spring-pressed releasing device controlled by the said movable door, substantially as described. 60

6. The motor for actuating a break-wheel and its main stop-arm $\vec{r}$, and co-operating stop, combined with the secondary stop-arm on the shaft of the break-wheel, and its movable stop adapted to be disengaged from the 65 said secondary stop-arm by the main stop-arm, substantially as described.

7. In a signal-box, the motor and its inclosing-case, adapted to be operated by a key inserted into the said box from the outside, and 70 means to engage the said key and prevent its withdrawal from the case, combined with the door of the case, which, when closed, acts to prevent the release of the said key, and which, when opened, permits the said key to be withdrawn from the case, substantially as described. 75

8. In a signal-box having a suitable dial, a pointer provided with an inclined surface, combined with a door having a suitable pulley or projection to strike against and move 80 the said pointer always to one position when the door is closed, substantially as described.

In testimony whereof we have signed our names to this specification in the presence of two subscribing witnesses.

JOHN CORNELIUS WILSON.
